US00D822913S

(12) **United States Design Patent** (10) **Patent No.:** **US D822,913 S**
(45) **Date of Patent:** **** Jul. 10, 2018**

(54) **AUTOMATIC PET WATER FOUNTAIN**

(71) Applicant: **Xiaocan Tao**, Guangdong (CN)

(72) Inventor: **Xiaocan Tao**, Guangdong (CN)

(73) Assignee: **SHENZHEN JINCAN PET PRODUCTS LIMITED.**, Fuyong Sub-Dist., Baoan District, Shenzhen, Guangdong (CN)

(**) Term: **15 Years**

(21) Appl. No.: **29/617,092**

(22) Filed: **Sep. 12, 2017**

(51) LOC (11) Cl. **30-03**

(52) U.S. Cl.

USPC **D30/132**

(58) **Field of Classification Search**

USPC D30/121–133; 119/51.01, 61, 51.04, 53, 119/57.91, 54, 53.5, 52.4, 51.11, 63, 61.2, 119/52.1, 57.5, 57.6, 51.13, 62, 75, 500, 119/501, 72, 72.5, 74, 78–81, 61.56, 51.5; 239/7, 687, 379, 397.5; 222/199, 181.1, 222/181.2, 185.1, 557, 156, 485, 486, 222/548, 555, 207, 205, 424, 438, 48, 222/206, 212, 215, 460, 461, 525, 86, 89; 220/200, 227, 247, 262, 694, 700, 701, 220/703, 660–662, 521, 705, 709, 287, 220/523, 574, 6, 771, 737, 23.83, 212, 220/4.22, 847; 221/174, 185.1, 289, 295, 221/296, 559; 454/35; 209/270, 283, 209/244; 52/194, 192; 49/279, 344, 357; D34/28; D9/531, 549, 516, 523, 530, D9/538, 541, 544, 559, 719, 716, 424, D9/426, 432, 428, 431, 433, 739; D7/300, 300.1, 302–305, 312, 316, 317, D7/507–512, 523, 524, 528, 700, 709, D7/605, 620, 612, 619.1, 624.2, 624.3, D7/550.1, 571, 587; D3/132; D15/143, D15/199; D28/4, 7, 9; D19/66; 141/343, 331, 340, 384, 330, 332, 383,

(57) **CLAIM**

The ornamental design for an automatic pet water fountain, as shown and described.

DESCRIPTION

FIG. 1 is a perspective view of an automatic pet water fountain showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
